UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,292,210.

Specification of Letters Patent. Patented Jan. 21, 1919.

Application filed June 9, 1916. Serial No. 102,641.

To all whom it may concern:

Be it known that I, CLIO B. YAW, citizen of the United States, and resident of Arlington, in the county of Hudson and 5 State of New Jersey, have invented certain new and useful Improvements in Type-Writing Machines, of which the following is a specification.

The present invention relates to paper 10 controlling and guiding means for type-writing machines. One object of the invention is to provide improved paper controlling and guiding means which include, first, feed roll devices which coöperate with the 15 platen and from which the platen may be swung away to facilitate the introduction of paper; second, a paper guiding device on the carriage which is associated with a stationary paper guiding device whereby long 20 sheets may be employed substantially in a flat condition; third, end stops for the paper, one of the end stops being movable with the carriage and the other end stop being stationary, the movable end stop being 25 settable out of the way so that a free passage for the paper or work sheet to coöperate with the stationary end stop is afforded. Other specific objects will hereinafter appear.

30 To the above and other ends my invention consists in the features of construction, combinations of devices and arrangements of parts hereinafter described and particularly pointed out in the claims.

35 The preferred embodiment of my present invention is illustrated in the accompanying drawings wherein—

Figure 1 is a fragmentary front to rear vertical view showing the rear part of a 40 typewriting machine embodying my invention.

Fig. 2 is a view corresponding to Fig. 1, but omitting some of the parts and showing other parts in different relationships.

45 Fig. 3 is a fragmentary front elevation partly in section of the upper portion of the machine.

Fig. 4 is a detail view of an end stop device and associate parts.

50 Fig. 5 is a fragmentary end view of the rear portion of the machine on a larger scale than Fig. 1.

Fig. 6 is a fragmentary rear elevation of the machine.

55 Fig. 7 is a rear elevation of the upper por-

tion of the machine, showing some parts not shown in Fig. 6 and omitting other parts.

Referring first particularly to Figs. 1, 5 and 7, the main frame of the machine is 60 shown as comprising a base portion or plates 1 from which rise uprights 2, that support a top plate 3. A guide-rail or track-way 4, grooved at its top and bottom, is detachably secured to the main frame. 65 Fixed by screws 4^a to the forward side of said guide-rail at its ends are uprights or extensions 5, each of which is provided at its top and bottom with cut-outs or hook portions 6 and 7. These hook portions are 70 adapted to engage or interlock with pins or projections 8 extending laterally outward from plates 9, which plates are detachably secured by screws 10 to the rear uprights 2 of the main frame. 75

The construction is such that the guide-rail 4 is secured in fixed relationship with the main frame. The guide rail 4 receives in the grooves at its top and bottom anti-friction balls 11, that coöperate with a slide 80 bar 12 that is part of a carriage, the slide bar housing the balls and embracing the track-way 4.

Devices are provided for preventing the separation or disconnection of the track-way 4 and the slide bar 12, these devices being in duplicate at the upper and lower sides of the track-way 4. With each set of balls 11 is associated a separator in the form of a plate 13 (Figs. 3 and 5), the 85 plate being perforated to provide openings for the balls which are thus maintained properly spaced apart as is usual. Each separator 13 is twisted and shaped near its ends to provide lugs or projections 14, which 90 lugs act as stops, coöperating with stops or projections 15 fixed in the bottom of the track portions of the slide bar 12. Relative endwise movements between the slide bar 12 and the track-way 4 are limited in both 95 directions by the stop devices 14 and 15, so that disconnection of the carriage from its bearing is prevented even when the parts have been detached and removed from the machine. 100

Besides the slide bar 12 the carriage further includes end bars 16 which are suitably fixed to the said slide bar at its rear side, and project upward and forward therefrom. Other end bars 17 fixed to the slide bar 12 110

outside the end bars 16 project downward. The carriage further includes a platen carrier or frame which is pivotally supported on the truck portion of the carriage hitherto described and including the slide bar 12 and two pairs of end bars 16 and 17. As described more in detail in my pending application Sr. No. 875,103, filed December 2, 1914, said platen frame comprises a cap or 5 housing 18 at the right-hand end of the frame and parallel cross bars 19 and 20, which are detachably fixed to said cap and extend leftward therefrom, being secured at their left-hand ends to the left-hand end 10 bar 21 of the platen frame. Journaled on the platen frame are the axle portions 22 and 23 of the axle of a cylinder platen 24. Coöperative with the front face of said platen are printing instrumentalities, not 15 shown, but which may be of any desired construction, such for example, as those illustrated in my Patent No. 1,237,439, granted Aug. 21, 1917. The cap or right-hand end bar or portion of the platen frame 18 is provided with a lug 18^a which receives a pivot 20 screw or connection 25 by which the right-hand end of the platen frame is pivotally connected to the end bar 16 at the right-hand end of the carriage. The left-hand end bar 25 21 of the platen frame is similarly pivotally connected at 26 to the left-hand end bar 16 of the carriage truck. The pivotal connection of the platen frame with the truck is, it 30 will be observed, below the platen and substantially beneath the platen axis.

In order better to control the swinging movements of the platen frame on the carriage truck, additional connections between the platen frame and said truck are employed comprising two pairs of links, one 40 pair at each end of the platen frame. Each pair comprises a short link 27 and a longer link 28, one end of each short link being connected to one of the end bars of the platen frame, and the other end being pivotally connected at 29 to the upper end of the longer link. The lower ends of the longer links are 45 connected to the carriage truck and preferably in order to synchronize movements are fixed to the outer end portions of a rock shaft 30 which takes bearings at its ends in the end bars 17. Fixed to the outer end of the end bar 21 is a finger piece or knob 31 by which swinging movements of the platen 50 may be controlled. The normal or forward position of the platen is illustrated in Fig. 1, and its rear or abnormal position in Fig. 2. Devices are provided for limiting the extent of swing of the platen and platen frame, said 55 devices comprising stop lugs 16^a which co-operate with end portions of the platen frame to arrest the platen frame (Fig. 2) when the platen is thrown back. In this position a wide gap or throat is provided between the platen and the paper feeding de-

vices which coöperate with its front face, said paper feeding devices serving also as stops to limit the forward swing of the platen and hold it in normal position.

The paper feeding devices comprise a feed 70 roller composed of sections 32 arranged lengthwise of the platen above the printing line and a similar feed roller comprising sections 33 arranged below the printing line. The sectional feed rollers are supported on 75 parallel shafts 34 which bear at their ends in rockers 35. Each rocker is pivoted at 36 midway between its ends on the adjacent end bar 16, which as shown in Fig. 3 is curved or off-set inward. Pins 37 projecting 80 outward from each rocker 35 engage loosely in slots 38 in the end bars 16 to limit rocking movements of the rockers 35. Said rockers together with the parallel shafts 34 85 constitute a rocking frame in which the platen seats itself when swung forward to its forward or normal position, as illustrated in Fig. 1. The platen is maintained in coöperative spring pressed engagement with the feed rollers 32 and 33 by spring means which 90 comprise two draw-springs 39, each anchored at its forward end to a pin 40 projecting upward from the slide bar 12, the rear end of each draw-spring being connected to one of the links 28 between its ends. 95 The action of the draw-springs is such that normally they hold the platen and the feed rollers in operative engagement while abnormally they hold the platen frame in contact with the stops 16^a and prevent rattling, 100 the springs having double-acting functions. The lower feed roller sections 33 coöperate with the face of the platen through openings 41 in a paper guiding contrivance or plate 42 which inclines downward and rearward, 105 under and behind the platen, and is secured by screws 43 to the slide bar 12, washers 44 being interposed between the guide plate 42 and the slide bar 12. The upper end portion of the guide plate 42 has secured to it 110 a scale bar 45. The rear end of the guide plate which terminates behind the slide bar 12 is near its lower end bent at right-angles from the body portion as indicated at 46. The sides 47 of the guide plate are bent upward at right-angles from the face thus providing a sort of trough for the paper which 115 may be readily inserted or "front fed" as it is called, when the platen is swung back to the Fig. 2 position. It will be noted that the relationship between the platen and its axle is constant, being the same when the platen is in the Fig. 1 or normal position as when the platen is thrown or swung back to the Fig. 2 position.

Mounted on the carriage are paper end stop devices, which devices are especially useful when a short sheet or card is employed. Said end stop devices, as illustrated in Figs. 1, 4, 6 and 7, comprise a rock shaft 120

or rod 48 which has fixed to it a stop blade 49, the ends of said rock shaft bearing in arms 50 fixed to the inner faces of the sides 47. Fixed to the left-hand end portion of 5 said rock shaft is a short crank arm 51 which is provided with an outwardly extending portion or off-set 51^a that carries a finger button 52. The right hand end portion of the rock shaft is provided with a lug 53 10 which coöperates with the free end of a leaf-spring 54 to hold the stop blade in either working or non-working position. The working position of the stop blade is shown in Figs. 1 and 4, from which it is clear that 15 the blade blocks the passage of the paper and provides an arresting face for the bottom edge thereof when it is introduced. By turning the finger button 52 the rock shaft may be rocked and the blade thrown to the 20 inoperative position indicated by dotted lines in Fig. 4 from which it will be understood that a clear passage is afforded for a farther downward advance of the paper. This, of course, is necessary when a longer sheet is 25 employed.

When longer sheets are used additional paper guiding and paper stop devices are preferably provided of the character illustrated in Figs. 1 and 6. Said devices include 30 what is in effect an extension of the movable or traveling guide plate 42, the extension, however, being stationary. The stationary guide plate designated as a whole by the reference numeral 55 comprises a surface or 35 table portion 56 suitably secured to a rectangular frame 57, said frame at its sides being provided with brackets 58 comprising parallel arms 59, 60, the longer arm 60 having a hole near its end, and the shorter arm 40 59 terminating in a semi-circular depression indicated at 61. The holes in the longer arms 60 fit over the reduced end portions of round extensions or rods 62 extending laterally outward from the rear portion of the 45 base 1, said arms being slightly yielding so as to enable them to be sprung over said rods. The depressions 61 in the arms 59 similarly fit over the reduced end portions of companion rods or pins 63 which project laterally outward from the base 1. Latches 50 64 pivoted to the brackets 58 coöperate with the rods or pins 63 to lock the table or guide device 55 in fixed relationship with the main frame. Said table it will be observed is inclined so that it is in the same plane as the 55 guide plate 42 and is virtually an extension thereof, the portion 46 of said guide plate being contiguous to the upper part of the frame 57. The stationary table or guide plate 55 inclines downward behind and below the typewriting machine and is of such length and width as to accommodate comparatively long wide sheets of paper which thus may be introduced into the machine and 60 fed out of it in a comparatively flat condi-

tion, this being an advantage especially where the paper is thick or somewhat stiff.

Additional paper stop devices are provided that are mounted on the stationary guiding device 55, said stopping devices as 70 shown in Figs. 1 and 6 comprising a blade or bar 65 extending crosswise of the table top 56 throughout its width and being provided at intervals with individual stops proper in the form of spring-pressed plungers 75 66 contained in housings 66^a secured along the bar 65. Said stops 66 coöperate directly with the surface of the table 56, these stops being in line so that they will properly arrest the bottom edge of the work sheet and 80 square it. The bar 65 is formed with an angularly bent portion 67 which projects upward at right-angles to the table top and is pivotally connected at 68 to the inner end of an arm 69, the outer end of said arm curving 85 downward and being provided with a hub 70 which bears slidably and rotatably on a guide rod 71, that is arranged at the left of the table top and extends parallel therewith, said guide rod being secured at its 90 ends to lateral projections 72 from the frame 57. A handle or finger piece 73 fixed to the arm 69 above its hub and extending laterally leftward affords a convenient means for throwing the stop bar 65 upward out of operative position. Pivotal movements of the stop bar on the arm 69 are limited by means of a screw 74 carried by said arm, which is engaged by a slot indicated at 75, which slot is formed in the left-hand end of the 100 angular portion 67.

The stop bar 65 is kept in coöoperative engagement with the table 56 by a spring means comprising a draw-spring 76 connected at one end to the arm 69, the opposite end of said spring being anchored to a plate 77 which is slotted at 78 to embrace loosely the sides of the arm 69 and is curved to seat itself against the hub 70 adjacent to said sides. The opposite end of said plate 110 77 coöperates with a rod 79 which is arranged parallel to the rod 71 between said rod and the side of the frame 57, said rod 79 being supported at its ends on the projections 72. The construction is such that when 115 the finger piece 73 is pressed down the arm 69 is swung up lifting the stop bar 65 from the plate 56 and enabling the whole stop contrivance to be slid up or down lengthwise of said plate to any desired position, 120 the range of the contrivance being substantially the length of the plate. The pivotal mounting of the stop bar 65 is such that the spring 76 maintains it in proper co-operation with the plate 56, the individual 125 springs of the stops proper 66 taking care of possible inequalities in the surface of the plate. The construction enables very long sheets of paper to be fed into the machine in a substantially flat condition and fed out 130

again without substantial bending. With the platen thrown back as in Fig. 2 the paper is inserted into the machine, its lower end passing through the wide throat or opening between the platen and the feed rollers 33 and 32, the paper passing downward over the supporting and guiding surfaces 42 and 56. The front feeding of the paper will continue until its bottom edge is arrested by the end stops 66, which, of course, have been previously adjusted so that when the paper is thus arrested it will be in position for receiving the first line of print. On the restoration of the platen from the Fig. 2 to the Fig. 1 position the paper will be held in proper relationship with the platen by the feed rollers 32 and 33 due to the pressure exerted by the springs 39. The width of the table 56 is such that it will support substantially the full width of the lower portion of the sheet even while the carriage is at the extreme limits of both its right-hand and left-hand travel. During carriage movements, of course, the lower portion of the paper will slide over the surface of the table 56, which remains stationary, a relative movement between the two portions 42 and 56 of the paper support or guide taking place during such carriage movements.

Endwise movements of the carriage are limited by stop devices, which, as illustrated in Figs. 3 and 7, comprise a toothed stop bar 80, which is mounted on the carriage being secured at its ends to the end bars 16. Adjustably mounted on said stop bar are margin stop devices comprising a bell trip 81, a line stop 82 and preferably two margin stops 83. These adjustable devices co-operate during endwise movements of the carriage with a rocking or stop member 84, which is mounted on the track-way 4 and is comprised in the train of line lock and bell ringing devices, the upper end of the rocking member 84 lying in the path of movement of the adjustable stop devices on the bar 80. Said member 84 is screwed to a shaft or bearing part 84^a which takes bearings in lugs 85, which are secured to the front face of the trackway 4. It will be observed that the margin stop devices comprise adjustable stops mounted on the carriage and the co-operating stop 84 mounted on the trackway 4, and further it will be noted that when the trackway is removed from the machine it results in the removal also of the stop bar 80 with its stop devices and also of the co-operating rocking device 84. The margin stop devices have the further function of preventing disconnection of the carriage from its trackway 4 when the parts are removed from the machine, so that they constitute a safety device for this purpose in case the stop devices 14, 15 should for any reason fail to work.

Step-by-step carriage feeding movements

are caused through operating the printing keys by escapement devices of suitable character, such for example as those partly illustrated in the drawings and described in detail and claimed in my Patent No. 1,237,439 aforesaid. Said escapement devices comprise a rack bar 86 mounted on the slide bar 12 (Figs. 5 and 7.) Said rack bar is provided with two sets of teeth, one meshing with a toothed wheel 87 mounted on the main frame and controlled by a spring drum which constantly urges the carriage leftward. The other set of teeth on the rack bar 86 co-operates with escapement devices proper that comprise a shaft 88 that has stationary bearings on the main frame and carries near its upper end a pinion 89, capable of limited slideable movement on the shaft 88. Said pinion 89 meshes normally with the rack bar 86 and is adapted to transmit movement to the shaft 88 by means of a clutch member 92 which is rotatably and slideably mounted on the shaft below the pinion 89, and is provided at its upper end with ratchet teeth which mesh with corresponding ratchet teeth formed in the under face of the pinion 89. Fingers 93 projecting downward from the clutch member at opposite sides of the shaft slideably engage with notches cut in a flange 95 on said shaft, the construction being such that the clutch member is forced to turn always with the shaft. Key controlled devices mounted on the carriage engage in a circumferential groove 96 in the clutch member, and are operative to move said clutch member downward on the shaft to disengage the ratchet teeth on the clutch member from the ratchet teeth on the pinion 89 so as to permit said pinion to turn freely on the shaft 88, thus releasing the carriage and permitting it to run freely leftward under the pull of its motor. The downward movement of the clutch member is in opposition to a spring 97 coiled around the shaft 88 which spring operates to maintain said clutch member normally engaged with the pinion 89 and also to restore said clutch member after the releasing operation. The lower end of the shaft 88 is provided with an escapement wheel which co-operates with escapement dogs not herein shown but preferably of the character disclosed in my application Sr. No. 855,551. The releasing devices mounted on the carriage comprise spring pressed release levers 98 and 99 pivoted respectively to the left-hand and right-hand end bars 16 on the carriage, and are provided at their upper ends with release keys 100 and 101. The ends of the lower arms of the release levers 98 and 99 are adapted to co-operate with fingers 102 fixed to opposite ends of a releasing plate or bar 103 pivoted on the carriage. Said release bar 103 is loosely supported on a rod 104 which

is secured at its ends to the bar 17. During endwise movements of the carriage the bar 103 slidably coöperates with a beveled roller 105 which is mounted on a pin 106 carried by a lever member 107 having a stationary pivot 108. The inner end of said lever member carries a pin 109 which engages in the groove 96. The construction is such that when one of the release keys 100 and 101 is pressed it operates to swing the release bar 103 on its pivot, causing said bar through the roller 105 to rock the lever member 107 on its pivot 108, the pin 109 carried by said lever member acting on the clutch member 92 to release the pinion 89 as has been described. It will be understood that when the carriage and its trackway are removed from the machine the releasing devices down to and including the bar 103 will also be removed while the coöperating parts from the roller 105 downward will remain on the machine frame.

My present invention embraces several important features and advantages some of which have not been claimed herein, *i. e.*, those relating to the mounting of the carriage and platen, since they are included in the subject-matter of my divisional application Serial No. 137,014, filed December 30, 1916.

It will further be understood that the principles of my invention by which I am enabled to provide a continuous supporting surface for a sheet of paper held substantially in a flat position while it is introduced into the machine and subsequently fed out of the machine more particularly in connection with visible writing machines of the cylindrical platen style, are such that the use of the invention is not confined to the particular arrangement or construction shown herein.

Various changes may be made without departing from my invention.

What I claim as new and desire to secure by Letters Patent, is:—

1. In a front-strike typewriting machine, the combination of a carriage, a platen movably mounted thereon, a paper feed roller device mounted on the carriage and coöperative with the front, printing face of the platen, a paper guide arranged below the platen and inclining downward away therefrom, said guide terminating at its upper end on the forward side of the platen, and means for affording a movement of the platen away from the paper feed roller so as to facilitate the front feeding of a sheet which is introduced between the platen and the feed roller and thence passes downward and backward under the platen and over said guide.

2. In a front-strike typewriting machine, the combination of a carriage frame, a platen frame mounted to swing back and

forth thereon, a platen on said platen frame, a feed roller device on said carriage frame and coöperating with the front, printing face of the platen, and a guide plate arranged on said carriage frame and extending below the platen, the swinging of the platen frame in one direction separating the platen from the feed roller and facilitating the front feeding of a sheet which is introduced at the front side of the platen between it and the feed roller device and thence passes downward and rearward below the platen and over the guide plate.

3. In a front strike typewriting machine, the combination of a carriage, a platen mounted thereon for relative movement with respect thereto, a paper controlling device coöperative with the platen both above and below the printing line thereon, and a paper guiding device mounted on the carriage below the platen, the platen being movable away from the paper controlling device to facilitate the front feeding of the paper into the machine over said paper guiding device.

4. In a front strike typewriting machine, the combination of a carriage, a platen mounted to swing thereon, a feed roller device coöperative with the platen above and below the printing line, and a guide plate mounted on said carriage below said platen, the platen being movable away from the feed roller device to facilitate the front feed of the paper into the machine over the guide plate.

5. In a front strike typewriting machine, the combination of a carriage, a platen mounted to swing thereon, a feed roller mounted on the carriage and coöperative with the front face of the platen, spring means for maintaining the platen in coöperative engagement with the feed roller, and a guide plate mounted on the carriage below the platen, the platen being movable against said spring means to facilitate the front feeding of the paper into the machine between the feed roller and the platen and over said guide plate.

6. In a typewriting machine, the combination of a carriage, a feed roller device comprising parallel sets of feed rollers mounted on a frame and pivoted at its ends intermediate said sets of feed rollers to the carriage, a platen movably mounted on said carriage, and spring means normally operative on said platen to press said platen into coöperative engagement with said feed rollers, the feed rollers being free from the control of said spring means when the platen and the feed rollers are disengaged.

7. In a front strike typewriting machine, the combination of a carriage, a platen mounted to swing thereon, a feed roller coöperative with the platen above the printing line, a feed roller coöperative with the platen below the printing line, a common

mounting for said feed rollers and a guide plate rigidly mounted on said carriage and inclining forward and upward, the forward end of said guide plate terminating at the 5 front of the platen and between said feed rollers, and the rear portion of said device terminating below and in rear of the platen.

8. In a typewriting machine, the combination of a carriage frame, a platen frame 10 mounted to swing back and forth thereon, a platen on said platen frame, a feed roller on said carriage frame, and an inclined guide plate on said carriage frame terminating at one end in front of the platen and 15 at the other end below and in rear of the platen, the sides of said guide plate below the platen being turned up to provide a chute.

9. In a front-strike typewriting machine, 20 the combination of a carriage, a platen, paper feeding devices coöperative with the platen at the front side thereof, means for affording a separation of said platen and said paper feeding devices, an inclined guide 25 plate mounted on the carriage below said platen, and an inclined guide plate mounted on the frame of the machine coöperative with said first recited guide plate.

10. In a typewriting machine, the combination of a carriage, a platen thereon, a 30 guide plate on the carriage, and a stationary guide plate coöperative with the first named guide plate to provide a substantially continuous supporting surface for the paper; 35 the said two plates being both arranged in alinement on the same side of the platen.

11. In a typewriting machine, the combination of a carriage, a platen thereon, a guide plate on the carriage arranged at an 40 angle to a horizontal plane, and a stationary guide plate contiguous to the first recited guide plate and arranged at the same angle of inclination.

12. In a front strike typewriting machine, 45 the combination of a carriage, a platen thereon, a guide plate mounted on the carriage below the platen, said guide plate inclining downward and rearward, and a stationary guide plate inclining downward and 50 rearward at the same angle as the first named guide plate.

13. In a front-strike typewriting machine, the combination of a carriage, a platen thereon, a guide plate mounted on the carriage 55 below the platen, said guide plate inclining downward and rearward, and a stationary guide plate inclining downward and rearward at the same angle as the first named guide plate, said stationary guide plate being wider 60 than the first named guide plate and its top edge being parallel with and adjacent to the bottom edge of the first recited guide plate in all positions of said carriage.

14. In a typewriting machine, the combination of a carriage, a platen thereon, a

guide plate on the carriage, a stationary guide plate coöperative with the first named guide plate to provide a contiguous supporting surface for the paper, and an end stop device on the stationary guide plate 70 adjustable toward and away from the platen.

15. In a typewriting machine, the combination of a carriage, a platen thereon, a guide plate on the carriage arranged at an angle to the horizontal plane, a stationary 75 guide plate contiguous to the first recited guide plate and arranged at the same angle of inclination, and a paper end stop device slidably mounted on said stationary guide plate for adjustment toward and away from 80 said platen.

16. In a front strike typewriting machine, the combination of a carriage, a platen thereon, a guide plate mounted on the carriage below the platen, said guide plate inclining 85 downward and rearward, a stationary guide plate inclining downward and rearward at the same angle as the first named guide plate, and an end stop for the paper coöperative with said stationary plate. 90

17. In a front strike typewriting machine, the combination of a carriage, a platen thereon, a guide plate mounted on the carriage below the platen, said guide plate inclining downward and rearward, a stationary guide 95 plate inclining downward and rearward at the same angle as the first named guide plate, an end stop for the paper coöperative with said stationary plate, and means for affording adjustment of said end stop up and 100 down along said stationary guide plate.

18. In a front strike typewriting machine, the combination of a carriage, a platen thereon, a guide plate mounted on the carriage below the platen, said guide plate inclining 105 downward and rearward, a stationary guide plate inclining downward and rearward at the same angle as the first named guide plate, and an end stop for the paper mounted on said carriage. 110

19. In a typewriting machine, the combination of a traveling platen, a traveling paper guide, a traveling end stop for the paper, a stationary paper guide, and a stationary end stop for the paper. 115

20. In a typewriting machine, the combination of a traveling platen, a traveling paper guide, a traveling end stop for the paper, a stationary paper guide, a stationary end stop for the paper, and means for affording 120 adjustment of said stationary end stop to vary the point at which the paper is arrested when introduced into the machine.

21. In a typewriting machine, the combination of a traveling platen, a traveling paper guide, a traveling end stop for the paper, a stationary paper guide, a stationary end stop for the paper, and means for moving 125 said traveling end stop into and out of operative position. 130

22. In a typewriting machine, the combination of a traveling platen, a traveling paper guide, a traveling end stop for the paper, a stationary paper guide, a stationary end stop for the paper, means for moving said traveling end stop into and out of operative position, and means for varying the normal location of said stationary end stop to vary the point of arrest of the paper on its introduction into the machine.

23. In a front strike typewriting machine, the combination of a carriage, a platen mounted thereon, a feed roller device co-operative with the front face of the platen, a guide plate mounted on said carriage below the platen and inclining downward and rearward, means for affording separation between said feed roller device and said platen, and an end stop for the paper arranged between said platen and said guide plate.

24. In a front strike typewriting machine, the combination of a carriage, a platen mounted thereon, a feed roller device co-operative with the front face of the platen, a guide plate mounted on said carriage below the platen and inclining downward and rearward, means for separating said feed roller device and said platen, an end stop for the paper arranged between said platen and said guide plate, and means for moving said end stop into and out of operative position.

25. In a front strike typewriting machine, the combination of a carriage, a platen mounted thereon, a feed roller device co-operative with the front face of the platen, a guide plate mounted on said carriage below the platen and inclining downward and rearward, means for separating said feed roller device and said platen, an end stop arranged between said platen and said guide plate, means for moving said end stop into and out of operative position, and a stationary end stop with which the paper co-operates when the first recited end stop is set in inoperative position.

26. In a front strike typewriting machine, the combination of a carriage; a platen mounted thereon; a feed roller device co-operative with the front face of the platen; a guide plate mounted on said carriage below the platen and inclining downward and rearward; means for affording separation between said feed roller device and said platen; and an end stop device for the paper comprising a blade pivotally mounted on the carriage and arranged to co-act only with the inclined guide plate to arrest the paper.

27. In a front strike typewriting machine, the combination of a carriage; a platen mounted thereon; a feed roller device at the front of the platen; a guide plate mounted on said carriage below the platen and

inclining downward and rearward; means for separating said feed roller device and said platen, and an end stop device for the paper comprising a blade pivotally mounted on the carriage and arranged to co-act only with said inclined guide plate, a finger piece connected with said blade for turning it into and out of operative position, and detent devices for maintaining said blade in both operative and inoperative positions.

28. In a front strike typewriting machine, the combination of a carriage; a platen thereon; a guide plate mounted on the carriage below the platen, said guide plate inclining downward and rearward; a stationary guide plate inclining downward and rearward at the same angle as the first named guide plate; and an end stop for the paper co-operative with said stationary platen and comprising a pivoted arm, and a second arm pivoted to said first named arm and provided with end stops proper.

29. In a typewriting machine, the combination of a platen; and end stop devices for the paper comprising a pivoted arm, a second arm mounted on and having a limited pivotal movement on said first arm, and a plurality of paper stops proper mounted on said second arm.

30. In a typewriting machine, the combination of a platen, a paper guide, a rod rigid with said paper guide, an arm pivotally supported on said rod and adjustable therewith, a second arm pivotally mounted on said first arm and having a limited pivotal movement, and a plurality of end stops on said second arm.

31. In a typewriting machine, the combination of a platen, a paper guide, a rod rigid with said paper guide, an arm pivotally supported on said rod and adjustable therewith, a second arm pivotally mounted on said first arm and having a limited pivotal movement, and a plurality of spring mounted end stops arranged lengthwise of said second arm.

32. In a typewriting machine, the combination of a platen, a paper guide, a rod rigid with said paper guide, an arm pivotally supported on said rod and adjustable therewith, a second arm pivotally mounted on said first arm and having a limited pivotal movement, a plurality of end stops on said second arm, and a spring tending constantly to press said first recited arm toward said guide.

33. In a typewriting machine, the combination of a platen, a paper guide, a rod rigid with said paper guide, an arm pivotally supported on said rod and adjustable therewith, a second arm pivotally mounted on said first arm and having a limited pivotal movement, a plurality of end stops on said second arm, a spring tending constantly to press said first recited arm toward said

guide, and a finger piece for swinging said first recited arm against said spring to facilitate adjustment lengthwise of said rod.

34. In a typewriting machine, the combination of a platen, a carriage on which said platen is supported, a movable paper guide arranged on said carriage below said platen and inclining downward and rearward, a stationary guide having the same inclination as said movable guide, and means for detachably supporting said stationary guide on the main frame of the machine.

35. In a typewriting machine, the combination of a platen; a carriage on which said platen is supported; a movable paper guide arranged on said carriage below said platen and inclining downward and rearward; a stationary guide having the same

inclination as said movable guide; and means for detachably supporting said stationary guide on the main frame of the machine, said means comprising pins extending laterally outward from the sides of said main frame, slotted arms extending downward from said stationary guide and engaging with said pins, and latches to maintain said slotted arms engaged with said pins.

Signed at the borough of Manhattan, city of New York, in the county of New York and State of New York this 8th day of June, A. D. 1916.

CLIO B. YAW.
